T. B. H. ASKIN ET AL

BALL MILL LINING

Filed Nov. 8, 1921

UNITED STATES PATENT OFFICE.

THOMAS B. H. ASKIN, OF DENVER, COLORADO, AND GUY H. RUGGLES, OF INSPIRATION, ARIZONA, ASSIGNORS TO FRANK E. MARCY, OF LOS ANGELES, CALIFORNIA.

BALL-MILL LINING.

Application filed November 8, 1921. Serial No. 513,684.

To all whom it may concern:

Be it known that we, THOMAS B. H. ASKIN and GUY H. RUGGLES, citizens of the United States, and respectively residing at Denver, in the county of Denver, State of Colorado, and Inspiration, in the county of Gila and State of Arizona, have invented certain new and useful Improvements in Ball-Mill Lining, of which the following is a specification.

10 This invention relates to linings for ball and grinding mills of the type in which wearing plates of iron or steel co-operate with pillow blocks secured to the lining plates or to the shell.

15 The principal object is to decrease the metal consumption per ton of material ground without decreasing the efficiency of the mill, or, otherwise stated, to effect a minimum scrapping of metal by providing wearing plates which wear evenly through to the shell and pillow block at the same time.

We attain this object by providing a lining which consists of pillow blocks and replaceable wearing plates which shroud the pillow blocks and also have a substantial bearing on the shell and which wear evenly and completely through to the pillow block and shell so that the pillow block is afforded an indefinite life or becomes, as it were, a permanent fixture, while the wearing plates are constantly renewed.

In the drawings forming a part hereof,—

Figure 1 is a fragmentary sectional view illustrating the shell of the mill with a section of the improved lining in place.

Fig. 2 is a plan view of the pillow block.

Fig. 3 is a plan view of the wearing plate.

Fig. 4 is an enlarged detailed section 40 through the pillow block and wearing plate.

The shell 1 is provided as is usual with a lining embodying pillow blocks 2 and wearing plates 3. Each pillow block has its outer surface 4 curved in coincidence with the

45 curvature of the shell, the relatively inner surface 5 of the block being of uniform curvature substantially reversed from that of the curved surface 4 and meeting the latter at the toe 6 of the block as an acute edge.

50 The pillow block gradually thickens from the toe toward and to a point slightly in advance of the heel 7, the remaining length of the pillow block being of substantially uniform thickness. The heel proper of the pil-

low block is of materially reduced thickness, 55 presenting a ledge 8 of nearly the full width of the pillow block, the ends of the ledge coinciding with a recess 9 cut under the heel of the pillow block at the respective ends thereof.

60 Each of the wearing plates 3 has its lower end position formed on a curvature as at 10 to snugly fit the upper curved surface 5 of the pillow block, the wearing plate meeting the shell 1 immediately in advance of the 65 toe 6 of the pillow block and projecting thence in contact with the shell, as at 11. The wearing plate is of substantial thickness at 12 where it overlies the pillow block and is then gradually reduced in thickness on a 70 line of regular curvature, as at 13, for the remaining length of the plate, to a degree corresponding to the desired wear resistance and mill capacity.

75 The relatively forward end of toe 14 of the wearing plate is recessed at 15 to receive the ledge 8 of the next adjacent pillow block, the respective ends of the wearing plate having lips 16 to engage in the undercut portions 9 of the pillow block.

80 The wearing plate is removably secured to the pillow block, by bolts 17 passing through an opening in the pillow-block, the heads of the bolt being received in slots 20 extending inwardly from each end of the wearing plate 3, as shown in Fig. 3, and the wearing plate and pillow block are formed with registering openings 18, 19 and 21 respectively to receive a fastening means for securing the 85 pillow block and wearing plate to the shell.

90 The wearing plates are preferably constructed of iron or steel and their design is such that they are worn through to the shell and pillow block without detriment to the latter. Thus a re-lining of the mill necessitates the replacement of the wearing plates only, the life of the pillow blocks being indefinite.

95 Having thus described our invention, we claim:—

1. A ball or grinding mill lining comprising a plurality of pillow blocks and wearing plates, the wearing plates overlying and protecting the pillow blocks, one edge of said pillow block being recessed at the ends adapted to receive the extended edges of the adjacent wearing plate.

105 2. A ball or grinding mill lining consist-

- 2
- ing of units, each unit including a wearing plate, and a pillow block, the latter contacting with the mill shell, and its width being less than, and wholly within that of the wearing plate.
3. A ball or grinding mill lining consisting of over-lapping units, each unit including a wearing plate, and a pillow block, the latter contacting with the mill shell, and its width being less than, and wholly within that of the wearing plate.
4. A ball or grinding mill lining consisting of units, each unit including a wearing plate, and a pillow block, and means for securing them to each other, the pillow block contacting with the mill shell, and its width being less than, and wholly within that of the wearing plate.
5. A ball or grinding mill lining consisting of units, each unit including a wearing plate, and a pillow block, and means for securing them to each other, the pillow block contacting with the mill shell, and its width being less than, and wholly within that of the wearing plate and means extending through the wearing plate and pillow block into the mill shell for securing the parts together.
6. A ball or grinding mill lining consisting of units, each unit including a wearing plate and a pillow block both of which are adapted to lie against the mill shell, the width of the pillow block being less than and wholly within that of the wearing plate, and means for securing said units to the mill shell.
7. A ball or grinding mill lining comprising a shell, a plurality of pillow blocks and wearing plates, the wearing plates wholly covering the pillow blocks and a substantial area of the shell, in advance of the pillow blocks, one edge of said pillow blocks being recessed at the ends adapted to receive the extended edges of said wearing plates, means for connecting said pillow block and wearing plates together and means for connecting both to said shell.
- In testimony whereof we affix our signatures.

THOMAS B. H. ASKIN.
GUY H. RUGGLES.
